G. M. NEWCOMER,
BALL GRINDING MILL,
APPLICATION FILED APR. 22, 1915.

1,177,648.

Patented Apr. 4, 1916.

UNITED STATES PATENT OFFICE.

GEORGE M. NEWCOMER, OF NEW YORK, N. Y., ASSIGNOR TO F. L. SMITH & CO., OF NEW YORK, N. Y., A CORPORATION OF NEW JERSEY.

BALL-GRINDING MILL.

1,177,648.

Specification of Letters Patent.

Patented Apr. 4, 1916.

Application filed April 22, 1915. Serial No. 23,004.

To all whom it may concern:

Be it known that I, GEORGE M. NEWCOMER, a citizen of the United States, residing in the borough of Manhattan of the city of 5 New York, in the county of New York, in the State of New York, have invented certain new and useful Improvements in Ball-Grinding Mills, of which the following is a specification, reference being had to the accompanying drawing, forming a part hereof.

The cylinders of ball grinding mills are commonly provided, both as to their end walls and their circumferential walls, with 15 liner plates of steel which are detachably secured in place in order that they may be removed and replaced readily when worn out. Such liner plates are subjected, in the operation of a mill, to a continuous and 20 severe pounding, which action, like that of peening hammers, results in a spreading of the metal on the working face and an elongation of each plate in all directions. If the bolts by which the plates are secured to the 25 shell do not give way the plates themselves are distorted, bulging inwardly into the mill. The walls of the mill are also sometimes distorted. Most frequently, however, the bolts by which the plates are secured to 30 the walls of the mill are broken. In any case permanent injury to the mill itself usually results and always more or less loss. The peening of the plates cannot be prevented.

It is therefore the object of this invention 35 to prevent the injurious results which follow from the peening of the plates. In accordance with the invention the plates are cut either part way through or entirely 40 through, that is, are grooved or slotted, along the lines in which the greatest strains are developed by the peening. In this manner space is provided for the flowing of the metal under the peening action and the 45 distortion of the plates, the distortion of the shell walls of the mill, and the rupture of the bolts are entirely prevented.

The invention will be more fully explained hereinafter with reference to the 50 accompanying drawing in which it is illustrated and in which—

Figure 1 is a view in transverse section, on the plane indicated by the line 1—1 of Fig. 2, of a ball grinding mill equipped with 55 the invention. Fig. 2 is a longitudinal sec-

tion of the same on the plane indicated by the line 2—2 of Fig. 1. Fig. 3 is a detail view of one sector of the end lining. Fig. 4 is a section on the plane indicated by the line 4—4 of Fig. 3, showing the end wall of 60 the mill as well as the end lining. Fig. 5 is a detail view in section, on a plane corresponding to that of Fig. 1, but on a larger scale. Fig. 6 is a face view of one of the 65 circumferential liner plates. Fig. 7 is a detail view of one of the circumferential liner plates in section on the plane indicated by the line 7—7 of Fig. 5.

Except as pointed out herein, the ball grinding mill in which the invention is indicated as embodied, may be of ordinary construction, comprising a cylinder *a* with end plates *b* and a supporting shaft *c*. Such a mill is charged with grinding bodies, such as steel balls, and with the material to be 70 ground and is then rotated. As the heavy grinding bodies tumble about in the mill they strike the inner circumferential walls with heavy blows and to some extent the end walls also. The action of the grinding 75 bodies and the material to be ground would quickly wear through the shell walls, both circumferential and end, if they were not protected. Therefore they are protected by heavy steel plates which are detachably 80 secured in place so that they may be removed and replaced when they are broken or worn out. The circumferential liner plates are usually lapped so as to form steps on the inner face of the wall to assist in the proper 85 movement of the grinding bodies and material to be ground, but the end plates usually present substantially plane surfaces. In the drawing the end liner plates are shown at *d* *d'* and the circumferential liner 90 plates at *e*.

The end liner plates are usually formed in segments which extend from the central opening to the circumference in one piece, each segment being secured by bolts to the 100 end plate *b*. In the present case, however, each segment is formed of separate plates, as *d* and *d'*, that is to say, each segment is cut entirely through, as at *d*², in a line concentric with the cylinder. Furthermore, 105 each plate, which is secured to the end wall *b* by several bolts, as at *d*³, is cut, either part way through or entirely through, as at *d*⁴, on the lines in which the greatest strains are developed by the peening action. 110

These lines of greatest strain, in such end plates, are found to be the circular lines between the two circular series of bolts and the radial lines between bolts of the same 5 circular series.

The circumferential plates *e*, usually somewhat thicker at one end than at the other, rest at the thinner end against the circumferential wall *a* and at the thicker 10 ends are held away from the shell *a* by the thinner ends of the next plates, which have overlapped, and usually by interposed filling pieces *f*, the bolts *g* which secure the circumferential plates in place passing 15 through bolt holes *g'* in the thicker ends of the plates through the spacing pieces *f*, and through slots *e'* in the thinner ends of the plates. The slots *e'* in the thinner ends of the plates permit the spreading of the plates 20 in a circumferential direction under the peening action, without distortion either of the plates or of the shell. To prevent, however, the injurious effect of the peening action in a longitudinal direction with respect to the axis of the mill, the plate is 25 cut, as at *e²*, in circumferential lines between the bolts by which the plates are secured in place, these being the lines in which the greatest strains are developed by the 30 peening action.

The end plates are shown as cut entirely through on the lines of the greatest strains while the circumferential plates are shown as cut only part way through. By the cutting 35 all the way through in lines of limited extent as shown in Figs. 3 and 4, the plates are not weakened to such an extent as to

make them liable to breakage. On the other hand, when the plates are cut only part way through, as indicated in Figs. 5, 40 6 and 7, the result mainly desired is accomplished, that is, the strains are relieved while the plate is new and heavy, and when the plate is worn to the bottom of the cuts it has then lost its strength to such an extent 45 that it is not likely to over-strain the bolts or to distort the walls of the mill.

I claim as my invention:—

1. In a ball grinding mill, the combination with the shell of the mill, comprising 50 a circumferential wall and end plates, of liner plates secured to one of said end plates, comprising segments spaced from one another along a line concentric with the axis of the mill, such liner plates being slotted also in radial lines to relieve the strains produced by the peening action on such plates.

2. In a ball grinding mill, the combination with the shell of the mill comprising a 60 circumferential wall and end plates, of liner plates secured to one of said end plates by bolts and comprising segments spaced from one another along a line concentric with the axis of the mill and between circular series of said bolts, such liner plates being slotted also in radial lines extending 65 from proximate edges of the segments between said bolts of the circular series to relieve the strains produced by the peening 70 action on such plates.

This specification signed this 21st day of April A. D., 1915.

GEORGE M. NEWCOMER.
